UNITED STATES PATENT OFFICE.

ERNESTO ALBANO, OF TURIN, ITALY, ASSIGNOR TO CESARE FERRERI, OF CARRÙ, CUNEO, ITALY.

HYDRAULIC WHISK.

Application filed June 15, 1923. Serial No. 645,801.

To all whom it may concern:

Be it known that I, ERNESTO ALBANO, a subject of the King of Italy, residing at Turin, Italy, have invented certain new and useful Improvements in Hydraulic Whisks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has for its object a hydraulic whisk used to whip liquids or drinks of all kinds either alone or with other ingredients such, for example, as crushed ice, for the purpose of the preparation of whipped iced drinks.

The said whisk or agitator is set in motion by a small hydraulic motor intended to be operated with water under pressure from the usual city water conduits. The agitator is placed at the bottom of the vessel intended to contain the liquid to be whipped, and is set in motion by the impeller of the hydraulic motor keyed directly on its vertical shaft issuing from below into the bottom of the vessel through a suitable stuffing-box, while the said impeller is placed inside an extension of the bottom of the vessel removably fitted upon a base to which is secured the distributor of the water under pressure.

A constructional form of the invention is illustrated by way of example in the accompanying drawing, of which,—Figure 1 shows the whole apparatus in vertical section, whilst Figures 2 and 3 are horizontal sections on the lines 2^x—2^x and 3^x—3^x respectively of Figure 1.

In the drawing, 1 is the truncated-conical vessel or container intended to contain the liquid to be whipped and, fixed below, for instance by soldering, to the bottom 2 and closed above by the removable cover 3. Under the bottom 2 the vessel 1 is provided with the cylindrical extension 16 which can be either cast all in one piece with the bottom 2, or it can be fitted, for instance by means of the nut 5 screwed to the central sleeve 2' of the bottom 2. The whole of the vessel is supported removably by the hollow base 4 through which the extension 16 passes. This extension 16 with its flange

16' rests on the base 4 and is locked in a fixed position by means of the pin 17 fixed to the base and fitting into a notch 16" of the flange 16' at the top of base 4. The agitator which can be of any shape, is composed, in the example shown in the drawing, of a hexagonal hub 6 provided on three sides with oblique blades 6' and of the shaft 7 fixed to the hub. The shaft is mounted vertically and capable of turning within the sleeve 2' from which it issues below through the lower cap 8 screwed to the said sleeve. The tightness along the seat of rotation of the shaft 7 towards the exterior is assured by the packing 9 located into a suitable chamber of the sleeve 2' and forced by the spiral spring 10 acting on the same packing and against the cap 8.

On the lower extremity of the shaft 7 the impeller of the hydraulic motor, composed for instance of a vane wheel 12 of the Pelton type, is keyed by means of its hub. Any axial movement of the shaft 7 is thus prevented by the hubs 6 and 11 acting on opposite ends of the sleeve 2'. The hydraulic wheel is fed by an inlet nozzle 13 for the introduction of the water, and fixed to the base 4, its tangential jet passing through a hole 18 of the extension 16 on the vanes 12. The nozzle 13 is connected to the base 4 and ends outside with a pipe 14 eventually provided with a cock, and to which the flexible pipe of the water supply is attached. The water which has acted on the wheel is discharged below through an energy destroyer such as a damping diaphragm 15 of wire netting, provided at the bottom of the extension 16 and passes internally to the base from which it is discharged through the discharge tube 4'.

The working is as follows:

Supplying the water under pressure to the nozzle 13, the jet acts tangentially on the vanes 12, puts the wheel 11, 12 into very rapid rotation and in consequence the agitator 6, which, with its blades 6', causes an energetic whisking action on the liquid or drink previously introduced into the vessel. The water which has served to make the vaned wheel work is gently discharged through the diaphragm 15 and by the outlet 4' of the base.

It will be evident that the invention is in no way limited to the arrangements above described and illustrated, but that, without

departing from its essential principle the invention may be modified as desired in any respect which may be considered advantageous or necessary under practical conditions.

I claim:

1. In a whisk the combination with a container, a cylindrical extension on the bottom thereof, having a hole therein, an agitator in said container, a shaft passing through the container into the extension to one end of which the agitator is secured, a Pelton wheel secured to the other end of said shaft in said extension and a jet device opposite said hole and delivering said jet substantially tangentially in the plane of said wheel, said container, extension and wheel removable as a unit from said jet device.
2. In a whisk the combination with a container, a cylindrical extension on the bottom thereof, having a hole therein, an agitator in said container, a shaft passing through the container into the extension to one end of which the agitator is secured, a Pelton wheel secured to the other end of said shaft in said extension and a jet device opposite said hole and delivering said jet substantially tangentially in the plane of said wheel, and an energy destroyer extending across said cylindrical extension, said container, extension and wheel removable as a unit from said jet device.
3. In a whisk, the combination with a hollow base having a jet device for directing a water jet substantially parallel with the base, of a container, a cylindrical extension on the bottom thereof having a hole opposite said jet device, an agitator in said

container, a Pelton wheel in said extension and a shaft connecting said agitator and wheel, said container, agitator, extension and wheel removable as a unit from said base and said extension forming a cover for said base, said container, extension and wheel removable as a unit from said jet device.

4. In a whisk, a container, a central sleeve on its bottom, an agitator in the container, a shaft for the agitator passing through said sleeve, a perforated cap for the lower end of said sleeve, a packing in the sleeve, a spring between the packing and cap and a water wheel on the shaft below the cap, said container agitator and wheel forming a removable unit.

5. In a whisk, the combination with a hollow base, having a water outlet at its bottom and a jet device in its side above the bottom; of a container, a cylindrical extension connected to said container having a flange seating on said base and having a hole opposite said jet, a central sleeve at the bottom of said container and extending into said extension, an agitator in said container, a shaft for the agitator extending through said sleeve, a Pelton wheel on the lower end of said shaft in said extension to receive a jet directed substantially in the plane of said wheel and an energy destroyer below said wheel extending over the lower end of said extension and discharging into said base, said container and extension with the elements mounted therein removable as a unit.

In testimony that I claim the foregoing as my invention, I have signed my name.

ERNESTO ALBANO.
